CUTTING BEVEL-WHEEL TEETH.

1,286,832.

Specification of Letters Patent.

Patented Dec. 3, 1918.

Application filed October 29, 1917. Serial No. 199,163.

To all whom it may concern:

Be it known that we, SAM SUNDERLAND, a subject of the King of Great Britain and Ireland, residing at High Utley, Keighley, 5 in the county of York, England, and ARTHUR MAURICE MIDGLEY, a subject of the King of Great Britain and Ireland, residing at Holly Bank, Sutton-in-Craven, near Keighley aforesaid, have jointly invented a 10 certain new and useful Improvement in Cutting Bevel-Wheel Teeth, of which the following is a specification.

This invention relates to bevel wheel cutting machines and has for its object to provide means whereby the cutter carrying plates may be operated in a direct and effective manner. These plates are so combined with a rotary former plate that said plate acts directly upon the free ends of the 15 pivoted frames, which carry the reciprocating cutters, and during the cutting of the bevel wheel teeth spaces are positively guided in accordance with the periphery of the former plate.

25 In describing our invention in detail, reference is made to the accompanying sheets of drawings, in which Figure 1 represents a side elevation of a bevel wheel cutting machine, to which our invention is added. Fig. 2 is a plan of the machine. Fig. 3 is an elevation looking to the right of Fig. 1, the swiveling pedestal carrying the wheel blank being shown at right angles to the reciprocating cutter plates in order to simplify the 30 drawings. Fig. 4 is a detached front view of the reciprocating cutter plates adapted to carry tool boxes of the ordinary description. Fig. 5 is a sectional view through line *a-b* of Fig. 4 showing how the sliding cutter plates may be supported. Fig. 6 is a detached view drawn to a larger scale, showing the curved slot in reciprocating plate. Fig. 7 a view of the opposite side of plate, showing the straight vertical slot. Fig. 8 is a detached plan view partly in section, showing the disk crank and engagement with vertical slot in reciprocating plate. Fig. 9 is a plan view of a shaft with a gear and collar mounted thereon showing the amount of 35 movement the collar may have. Fig. 10 is a vertical section of Fig. 9. Figs. 11, 12 and 13 represent respectively a sectional elevation, plan and elevation of a right and left-hand screw-threaded bar.

50 55 In carrying out our invention, we utilize

a bevel wheel teeth cutting machine of the type such as shown by the drawings, in which the bevel wheel blank 1, is secured to a spindle 2, supported by an adjustable pedestal 3, bolted to a swiveling plate 4, attached to ring segment 5, adapted to be moved to and fro in its circular path, moving the wheel blank 1, into and out of engagement with the reciprocating tools 6, the distance as may be required by the pitch and depth of tooth spaces to be cut.

The movement of ring segment 5 in its circular path, may be effected by a rotating worm 7, secured on shaft 7^A, the worm meshing with toothed segment 8, attached to ring segment 5, said shaft being rotated in both directions in the manner as hereinafter described.

This rotation may be effected during the teeth space cutting process, by a chain 9 engaging with sprocket wheels 10 and 11, the former wheel being rotated, by suitable connections with the shaft upon which the step driving pulley 12 is secured.

Sprocket wheel 11, is secured to sleeve 13 80 freely mounted on shaft 7^A, and during the teeth space cutting process, the clutch teeth 14, engage with like teeth on one end of sleeve 15, as shown by Fig. 1, said sleeve being feather keyed on shaft 7^A.

85 Each end of sleeve 15 is provided with clutch teeth, those at 16 engaging with like teeth 17, on sleeve of bevel wheel 18, so that on the sliding of bar 19 toward the right, on the completion of the cutting of each tooth space, the rotation of shaft 7^A is reversed, and ring segment 5 operated in the opposite direction to that shown by curved arrow 20 in Fig. 2, the continuous rotation of bevel wheel 18, being effected by geared connections 20, see Fig. 2, with friction pulley 21, driven by a separate belt.

The friction pulley 21 is of the usual type of construction, revolving along with sleeve 22, associated in the usual manner with the 100 indexing change gears 23 of the spacing device, the rotation of which is periodically prevented by any of the well known arrangements applied during the cutting of a tooth space, during which time, the ring segment 105 is moving in the direction shown by the curved arrow in Fig. 2.

When a tooth space has been cut to the required depth, the dog 24, bolted to ring segment 5, on coming in contact with an ex- 110

tension from collar C secured on bar 19, slides said bar toward the right, thereby sliding sleeve 15, and bringing into engagement the clutch teeth at 17, with those on sleeve integral with bevel wheel 18, by which means the rotation of shaft 7^a and worm 7, are reversed, causing ring segment 5 to be moved in the opposite direction to that shown by the curved arrow, sliding wheel blank 1 back, clear of cutters 6, to the position occupied before commencing to cut each tooth space.

The description so far applies to a machine suitable for working in combination with our invention which is added thereto; to this machine apart from the combination with our invention no claim is made.

The essential features of the invention are to arrange mechanism for cutting tooth spaces in wheel blanks, by the employment of two cutters mounted side by side acting simultaneously on the wheel blank, the cutters moving toward each other as controlled by a former plate adapted to be rotated part 25 of a revolution in each direction.

The step cone pulley is keyed upon a shaft upon which is secured a pinion (not shown by the drawings) meshing with a spur wheel 25, keyed upon a shaft 26, see Fig. 8, to 30 which is secured a disk 27, provided with a crank pin 28, carrying a sliding block engaging with a straight vertical slot 29, cut in plate 30, to which a reciprocating motion is imparted on the rotation of crank disk 27.

This plate is also provided with a curved slot 31, of quicker curvature than would be the case if the curve was struck from the center of circular pin 32, see Figs. 2 and 8, the pin being utilized for supporting one 40 end of the upper and lower reciprocating slide carrying frames 33 and 34, the lower frame 34, being provided with an extending arm 35, from which is suspended a weight 36, sufficient to cause the upward tendency 45 of slide carrying frame 34, to be about equal to the gravity or downward tendency of the upper frame 33, thus by these means equalizing the pressure on the former plate 37, applied and operated in the manner as 50 hereinafter-described.

Each pivoted frame 33 and 34 is provided with a reciprocating plate 38, each plate adapted to carry a tool box 39 of suitable description to which cutters 6 are secured.

Projecting from the rear of each plate is 55 a bar 40 integral therewith, see Figs. 5 and 8, each having a circular end carrying a block 41, engaging with the before mentioned curved slot 31, so that on the reciprocation of plate 30, a like movement is imparted to the tool box 39, carrying plates 38, and by the curvature of slot 31 being struck at a less radius than from the center of 60 circular pin 32. The quickness of the curve 65 insures the pressure of the slide carrying

frames 33 and 34 upon the periphery of the former plate 37, allowing a free reciprocating movement to plates 38, the guiding of these plates and free ends of slide carrying frames being controlled as to distance apart 70 during the cutting process by contact of the anti-friction rollers 35 with the periphery of the rotating former plate 37.

Upon shaft 7^a is secured a skew toothed wheel meshing with a like wheel 42, freely 75 mounted on vertical shaft 43, near the lower end of which is secured a circular collar 44, having a pin P projecting downward, see Figs. 9 and 10, engaging with a recess R formed in the upper face of wheel 42, the recess R extending to three-fourths the circumference of said wheel, by which arrangement the skew toothed wheel 42, may make nearly one-half of a revolution in either direction, without affecting the rotation of vertical shaft 43, to the upper portion of which is secured a worm 45 meshing with a worm wheel 46 freely mounted on the horizontal shaft carrying the former plate, supported by the tubular bracket B, 80 adapted to swivel to some extent around the vertical shaft 43, in order to facilitate the changing of former plates suitably mounted and secured to shaft 47.

Worm wheel 46 is provided with clutch 85 teeth meshing with those cut in circular block 48, the block being feather keyed on shaft 47, the clutch teeth being held in mesh on the tightening of nut N. On the liberation of this nut circular block 48 may be 100 withdrawn clear of the clutch teeth cut in worm wheel 46, enabling the position of former plate 37 to be adjusted in a circular direction to the required position by the turning of horizontal shaft 47. 105

As before mentioned, one end of frames 33 and 34 is supported by circular pin 32, leaving the opposite end of frames free for adjustment as to distance apart on turning the right and left hand screw threaded bar 110 49, as required to suit the pitch and cone angle of the bevel wheel to be cut.

Each frame is provided with an adjustable bracket 50, carrying anti-friction rollers 51, engaging with the upper and lower 115 portions of periphery of former plate 37, see Fig. 3. The former plate on turning in a rotary direction, guides the free ends of frames 33 and 34, on the rotation of former plate by vertical shaft 43. 120

When a tooth space has been cut to the depth required, as before stated, the ring segment 5 is moved in the direction opposite to that shown by the curved arrow in Fig. 2, during which period the rotation of the former plate is stopped until pin P engages with the opposite end of recess R, thereby turning the former plate back to its original position before commencing to cut another tooth space. 125

During this reversal, shaft 22 is liberated in the ordinary manner, and the wheel blank 1 is turned in a rotary direction equal to the pitch of the teeth being cut, on the completion of which, the ring segment 5, is moved in the direction shown by the curved arrow in Fig. 2, thereby bringing into contact the wheel blank 1 with the reciprocating cutters 6.

10 Immediately the wheel blank arrives in contact with the cutters 6, the pin P will have arrived at the opposite end of recess R, putting into operation the rotation of the former plate 37, thereby guiding the frames 15 33 and 34, in accordance with the periphery of former plate, when the cycle of operations is repeated.

By stopping the rotation of vertical shaft 43, for a period before the engagement of 20 cutting tools 6, with wheel blank 1, any back lash there may be in the gears operating the wheel blank and former plate is removed before the cutting tools 6 engage with the wheel blank, thus securing accurate 25 in cutting the teeth spaces.

The free ends of the slide carrying frames 33 and 34 are adjusted to the proper distances apart to suit the thickness of the teeth to be cut relative to the pitch, said 30 frames being separated on the rotation of graduated hand wheel 52, see Figs. 11, 12 and 13, representing respectively a sectional elevation, plan and elevation of the right and left hand screw threaded bar 49. The 35 nuts 53 of the threaded bar 49 are not attached to the slide carrying frames 33 and 34, but the frames are provided with projections on the inner surface, one on each frame, in a position adapted to engage with 40 projections 54, on nuts 53, so that on the rotation of the threaded bar 49 the position or degree of angularity of the slide carrying frames 33 and 34, and cutters 6 as to distance apart will be adjusted to suit the 45 thickness of the teeth to be cut, the periphery of the rotary former plate 37 controlling the frames 33 and 34, and cutters 6 during the cutting of the bevel wheel teeth.

Antifriction rollers 51 are in contact with the plate 37, being held thereto by nuts 55. 50

When this is accomplished, the threaded bar 49 is turned in the opposite direction sliding the nut projections 54 clear of the projections on the inner surfaces of pivoted frames 33 and 34 leaving said frames free 55 to be operated in accordance with the periphery of former plate 37.

What we claim as our invention is:—

1. In a bevel wheel cutting machine, a ring segment adapted to be moved to and fro, a swiveling plate having an adjustable pedestal attached thereto, a spindle for carrying the wheel blank supported by said pedestal, a plate provided with vertical and curved slots, means for reciprocating said plate, a former plate, frames pivoted at one end to a circular pin and having their opposite ends free to engage with the periphery of a rotary former plate, slides supported by said frame and means for operating the 70 slides, substantially as described.

2. A bevel wheel cutting machine comprising a ring-segment adapted to be moved to and fro, a swiveling plate having an adjustable pedestal attached thereto, a spindle 75 for carrying the wheel blank supported by said pedestal, a plate provided with vertical and curved slots, means for reciprocating said plate, a former plate, means for delaying the rotary movement at the commencement and termination of each series of cuttings of teeth spaces, a circular pin, frames pivoted at one end to the circular pin, and having their opposite end free to engage with the periphery of the former 80 plate, slides supported by said frames and means for operating the slides, substantially as described.

In witness whereof we have hereunto set our hands in the presence of two witnesses. 90

SAM SUNDERLAND.
ARTHUR MAURICE MIDGLEY.
